UNITED STATES PATENT OFFICE

2,167,932

MATCH BOOKING MACHINE

Eric P. Olson, Brooklyn, N. Y., assignor to The Diamond Match Company, New York, N. Y., a corporation of Delaware

Application November 12, 1938, Serial No. 239,976

5 Claims. (Cl. 93—2)

This invention relates to match booking machines, and more particularly to a machine of the type embodying mechanism whereby flexible covers are successively positioned in the active path of an oscillating blade which is effective to fold each cover at one end and insert it in an intermittently movable carrier by means of which the end-folded covers are borne progressively to match assembling and other mechanisms, including a mechanism whereby the extended ends of the covers are folder about the heads and upon the stems of the matches contained in the respective covers. A machine of the type referred to is disclosed in United States Patents No. 1,042,472, dated October 29, 1912, No. 1,479,481, dated January 1, 1924, and No. 1,886,496, dated November 8, 1932, to which patents reference may be had.

The principal object of my invention is to provide simple and efficient means adapted and arranged to score or groove each succeeding cover in spaced parallel lines properly located to afford transverse hinge portions which ensure the folding of the extended end of the cover in a manner to present in the completed match book a neat and uniform end portion encasing the heads of the contained matches.

To this end my invention comprises novel features of construction and combinations of elements arranged in co-operative relation to the initial cover folding mechanism of the machine, as will be hereinafter described and claimed.

In the drawings—

Figure 1 is a partial rear elevation of the cover receiving end of a match booking machine equipped with scoring or grooving mechanism embodying the principle of my invention.

Fig. 2 is a partial front elevation showing the cover feeding, folding and scoring mechanisms.

Fig. 3 is a transverse vertical section through one of the folding blades and associated parts, as on the line 3—3 of Fig. 2.

Fig. 4 is a transverse horizontal section through the cover magazines, as on the line 4—4 of Fig. 2.

Figs. 5 and 6 are transverse vertical sections, as on the lines 5—5 and 6—6, respectively, of Fig. 1.

Fig. 7 is a partial sectional elevation adjacent one of the cover magazines, the section being taken through one of the chambered suction slides, the upper end of the slotted folder member, and the vertically movable die element for scoring or grooving the covers, one of which covers is represented as supported on the slide with one end overlying the mouth of the folder

member, and the die element being shown in down or acting position on the cover.

Fig. 8 is a transverse vertical section, as on the line 8—8 of Fig. 7.

Fig. 9 is an end elevation of one of the chambered slides and the overhanging die element preparatory to the scoring or grooving of a cover imposed on the slide.

Fig. 10 is a detail of the die bars and the end connecting members thereof.

Fig. 11 is a perspective view of one of the chambered slides and the grooved insert therein with which the movable die element co-operates.

Fig. 12 is a general perspective view of one of the slides, the movable die element co-acting therewith, and the tappet for positioning the cover in accurate relation to such element, showing the operating connections for the slide, the movable die element and the tappet.

Fig. 13 illustrates a scored or grooved cover. 20

Fig. 14 illustrates a match book having the said cover applied thereto.

Referring to the annexed drawings, 15 designates the supporting frame including the table 16 of a match booking machine, 17 designates the intermittently-movable pocketed carrier whereof the upper run is guided in a trough 18 on the table, and 19 designates the driven cam shaft which, through suitable cam and transmission mechanisms, actuates the carrier and other moving parts of the machine. 25

Spaced cover-containing magazines 20 are supported by brackets 21 on the table, and horizontal chambered slides 22, which are mounted in guideways in the respective brackets, constitute bottoms for the magazines. The top of each slide is provided with a perforated area 23 and the chamber of the slide is connected at one end by means of a flexible tube 24 to an air pipe 25

in controllable communication with a suitable pump (not shown), whereby air is periodically removed from the chamber and the lowermost cover (C) in the magazine is thus held flatwise upon the perforated area. Hence by reciprocating the slide to move such area under and beyond the magazine each succeeding lowermost cover is removed from the magazine, the respective ends of the cover projecting beyond the slide, as seen in Fig. 3. In the present instance means 30

for simultaneously actuating the slides comprises a pair of levers 240 which are suitably mounted beneath the table and are jointed at their upper ends to the respective slides, the lower ends of the levers being equipped with rolls 250 which 35

50

55

55

run in peripherally grooved cams 26 on the shaft 19. (See Fig. 1.)

Channelled folding members 27 are supported on the inner sides of the respective brackets 21.

- 5 In each member is formed from top to bottom a curved channel 28 whereof the outer side is open and the top is directly below the adjacent cover when it is withdrawn from the magazine by the "suction" slide 22. Curved folding blades 29 corresponding with the respective channels of the members 27 are arranged and adapted to swing into and from the channels. Each blade in its downward stroke engages the opposing end portion of the cover and tucks it down into and 10 through the adjacent channel, thereby effecting the folding of such end, and carrying the fold end of the cover through and just beyond the opposing link of the intermittently movable carrier.

The two blades 29 are borne by arms 30 which are mounted on and concurrently operated by a rock-shaft 31 having its bearings in brackets 32 rising from the table. Fast on the rock-shaft 31 is a gear sector 33 in mesh with a similar sector 34 fast on a rearward parallel rock-shaft 35 having its bearings in the walls of the slotted body portion 36 of a standard 37 which rises from the table and supports the air pipe 25. The shaft 35 is encircled by a torsional spring 38, whereof one end is secured to the shaft 35 and the other end to a crank arm 39 loose on such shaft. This crank arm has a lateral stud or projection 40 which is normally urged by the action of the spring in contact with a toe 41 fast on the shaft 35. The crank arm 39 is connected 30 by means of a link 42 with a rocker-arm 43 bearing a roll 44 which runs in the race of a cam 45 fast on the driven cam shaft 19 of the machine. The contour of the cam race is such as to effect through the connections just described oscillatory motion of the rock-shaft 35, thus through the agency of the meshing sectors 33 and 34 oscillating the folding blades.

When the blades are up the slides are pushed endwise toward each other to carry the imposed covers and locate the rearwardly projecting ends of the latter directly under the blades, which blades then descend upon the opposing ends of the covers. The slides then remain at rest for an interval and move back toward the magazines. 45 When the slides are about half way back the folding blades have reached their extreme down position. In the next or return stroke of the blades the slides continue back to their original position under the magazines in readiness to push forward the next succeeding covers. The portion of the carrier supported on the table is intermittently driven to present two of the links to the open ends of the respective channels 28 of the folding members 27 in timed relation to the 50 operation of the folding blades so as to receive the end folded covers.

The mechanisms thus far described are set out in detail in the patents previously mentioned.

Cover scoring or grooving mechanisms embodying a practical form of my invention are illustrated as arranged in cooperative relation to the respective "suction" slides 22 of the machine. As the mechanisms are alike a description of one will suffice, as follows: The perforated top portion 23 of each of the slides includes a perforated insert section 46 having therein spaced parallel grooves 47 which are arranged to underlie and define that portion of the cover which is to be bent about the heads of the matches after the latter have been associated

with the cover. The perforated section is provided at one end with a lip 48 which is detachably secured to the adjacent wall of the slide, as by screws 49. Overlying the section 46 when the rearward end of the book cover thereon is located in the path of the folding blade, are a pair of parallel die ridges 50 arranged above and in cooperative relation to the corresponding grooves 47 of such section. These ridges are conveniently formed on a pair of T-bars 51 whereof the webs are snugly fitted in the parallel slots 52 of a housing 53, which is bolted to the free end of the longer arm 54 of a vertically movable rock lever hereinafter described. The ends of the bars 51 are recessed, as at 55, for the 10 slidable reception of tie plates 56 whereof the upper edges are notched, as at 57, to receive the upper end projections 58 of the respective bars. The plates bear against the opposing ends of the housing and are secured thereto as by screws 59, 20 the notches of the bars being of sufficient depth to permit slight sliding vertical movement of the connected bars. The housing 53 has therein vertical sockets 60 containing compression springs 61 which, being confined by the adjacent face of 25 the lever, bear upon heads 62 within the sockets, which heads, in turn, press against the opposing bars 51 and tend to urge them downward to a limited extent. Hence the die bars are caused to exert resilient pressure on the cover when by 30 proper actuation of the lever arm 54 they are pressed downward in co-operative relation to the complementary grooves 47, thus effecting the transverse scoring or grooving of the body of 35 the cover, as seen in Figs. 7, 8 and 9. The cover, C, with its spaced parallel grooves c is shown in Fig. 13, and a book of matches embodying the grooved cover is shown in Fig. 14, such cover being represented as folded along the grooves to provide a uniform end portion d at the heads of 40 the contained matches.

The lever hereinbefore referred to is fulcrumed, as at 63, on one of two adjacent upstanding brackets 64 which are supported by the table, and are fixedly connected at their upper ends by a 45 tie piece 65 which is bolted to the standard 37 previously referred to. The shorter arm 66 of the lever is connected by means of a link 67 with an upper rock arm 68 parallel with the arm 66. The rock arm 68 is fast on a longitudinally extending shaft 69 which has its bearings in the bracket 64 and also in a suitably-located bracket 70 rising from the table. (See Fig. 1). The end of the shaft 69 adjacent the bracket 70 has fast thereon an arm 71 which is connected by 55 means of a depending link 72 with one arm 73 of a bell-crank fulcrumed on a base bracket 74 adjacent the cam shaft 19. The other arm 75 of the bell-crank is provided with a roll 76 which is held in operative contact with the periphery of 60 a cam 77 on the shaft 19 by means of a spring 78, which spring is secured to the arm 73 and to a stationary part of the machine. The contour of the cam 77 is such that in an interval of its rotation when the cover borne by a "suction" 65 slide is positioned beneath the die bars 51 such bars are lowered and raised through the operation of the lever and link connections just described.

In order to insure the accurate positioning of 70 each succeeding book cover in relation to the grooves 47 of the perforated insert section 46 immediately preceding the descent of the die bars, a vibratory tappet 79 is arranged and adapted to act upon the projecting forward end 75

of the cover. This tappet comprises a horizontally disposed member slidably fitted in a guide fixture 80 on the forward upper flange 81 of the channelled folding member 27. One end of the 5 tappet has a bearing face 790 shaped to impinge against and throughout the length of the opposing end of the cover, and the other end is provided with lateral ears 82 equipped with adjusting set screws 83 which co-act with the opposing 10 edge of the flange 81 in order to adjust and determine the limit of inward movement of the tappet in respect to the cover. The tappet is jointed, as at 84, to the upstanding arm 85 of a lever which is fulcrumed, as at 86, on an ear 87 15 extending forwardly from the adjacent rib of the magazine supporting bracket 21. The tappet is held normally outward by means of a spring 88 which is secured to the other arm 89 of the lever and to the adjacent bracket 21. The arm 20 89 is pivotally connected by means of a link 90 with the longer arm 91 of a bell-crank which is pivoted on the table, as at 92. The shorter arm 93 of the bell-crank has pivoted thereto, as at 94, a toe 95 which extends into the path of the 25 lever 240 for actuating the adjacent cover slide 22, such toe being maintained yieldingly in normal position by the action thereon of a buffer block 96 carried by the free end of a spring strip 97 which is secured to the short arm of the bell-crank, as at 98.

By the construction just described the lever 240 30 as it completes its transfer stroke from the adjacent cover magazine to the end folding position, and at the instant the vacuum within the chamber of the slide is temporarily broken, abuts 35 against the spring pressed toe 95 and imparts to the bell-crank 91, 93 and the lever 85, 89 a slight swinging motion effective to move the tappet 79 inward against the opposing end of the cover, thus 40 squaring the cover on the perforated portion of the slide and accurately locating it above the perforated grooved section preparatory to the descent of the overlying folding blade upon the rearwardly projecting end of the cover. In the 45 return stroke of the lever 240 toward the magazine and away from the spring pressed toe 95, the tappet resumes its normal outward position. The provision of the spring pressed toe on the bell-crank arm 93 operates as a buffer to reduce 50 the jar otherwise resulting from the impact of the rapidly swinging lever on the bell-crank.

It is to be understood that the invention is not limited to the particular exemplifying form thereof herein disclosed, as the mechanisms may be 55 modified within the principle of the invention and the scope of the appended claims.

I claim—

1. In a booking machine, the combination of a 60 magazine for flexible covers, cover folding means adjacent said magazine, means including a transfer member arranged and adapted to withdraw each succeeding cover from the magazine and position the cover with one end thereof in the effective path of the folding means, die means in co-operative relation to said transfer member to groove the body of the cover transversely in spaced parallel lines before the action of the folding means on the positioned cover, thus providing the cover with hinge portions, and means for operating said die means in timed relation to the folding 65 means.

2. In a booking machine, the combination of a

magazine for flexible covers, cover folding means adjacent said magazine, cover transfer means including a member having a suction chamber with a perforated wall area to receive each succeeding cover from the magazine and position the cover with one end thereof in the effective path of the folding means, said perforated area having therein spaced parallel grooves which underlie the body of the cover, a die element in co-operative relation to the grooved portion of said area to depress the body of the cover transversely in spaced parallel lines before the action of the folding means on the positioned cover, thus providing the cover with hinge portions, and means for operating said die element in timed relation to the folding 15 means.

3. In a booking machine, the combination of a magazine for flexible covers, cover folding means adjacent said magazine, cover transfer means including a member having a suction chamber with a perforated wall area to receive each succeeding cover from the magazine and position the cover with one end thereof in the effective path of the folding means, said perforated area including a 20 perforated insert section having spaced parallel 25 grooves which underlie and extend transversely of the body of the cover, a die element in co-operative relation to the grooved section to depress the body of the cover into the respective 30 grooves before the action of the folding means on the positioned cover, thus providing the cover with hinge portions, and means for operating said die element in timed relation to the folding means.

4. In a booking machine, the combination of a magazine for flexible covers, cover folding means 35 adjacent said magazine, means including a transfer member arranged and adapted to withdraw each succeeding cover from the magazine and position the cover with one end thereof in the effective path of the folding means, die means in 40 co-operative relation to said transfer member to groove the body of the cover transversely in spaced parallel lines before the action of the folding means on the opposing end of the cover, thus 45 providing the cover with hinge portions, a vibratory tappet for acting on the opposite end of the cover to ensure the accurate relation of the cover to the die means, and means for operating said cover grooving means and tappet in timed relation to each other and to the folding means. 50

5. The combination of a magazine for flexible covers, cover folding means including a reciprocating blade adjacent said magazine, actuating means for said blade, means including a transfer member arranged and adapted to withdraw 55 each cover from the magazine and position the cover with one end thereof in the effective path of the folding blade, means including a lever for reciprocating said transfer member, die means in co-operative relation to said transfer member to 60 groove the body of the cover transversely in spaced parallel lines before the action of the folding blade on the opposing end of the cover, thus providing the cover with hinge portions, a vibratory tappet for acting on the opposite end 65 of the cover to ensure the accurate relation of the cover to the die means, and connections between said lever and the tappet for operating said tappet in timed relation to the cover grooving means and the folding blade. 70

ERIC P. OLSON.
